UNITED STATES PATENT OFFICE.

ROBERT E. BOLLES, OF NEW YORK, N. Y., ASSIGNOR TO FOWNES BROTHERS & CO., A FIRM COMPOSED OF WILLIAM GARDINER RIGDEN, WILLIAM FOWNES RIGDEN, EDWARD FOWNES RIGDEN, STANLEY FOWNES RIGDEN, SIR HENRY URWICK, AND LESLIE ALAN SPALL, OF LONDON, ENGLAND.

DESIGN FOR A GLOVE.

49,986.

Specification for Design.

Patented Dec. 5, 1916.

Application filed March 17, 1916. Serial No. 84,985. Term of patent 3½ years.

To all whom it may concern:

Be it known that I, ROBERT E. BOLLES, a citizen of the United States, residing in the borough of Bronx, city of New York, county of Bronx, and State of New York, have invented a new, original, and ornamental Design for Gloves, of which the following is a specification, reference being had to the accompanying drawing, forming part thereof.

The drawing is a plan view of the glove showing my design.

I claim:

The ornamental design for a glove substantially as shown.

In testimony whereof, I have hereunto subscribed my name.

ROBT. E. BOLLES.

Witnesses:

P. V. HEATON,
A. CARR.
